UNITED STATES PATENT OFFICE

2,546,426

GOLF CLUB INDICATOR

Albert H. Bryant, Floyds Knobs, Ind.

Application June 27, 1949; Serial No. 101,630

10 Claims. (Cl. 33—174)

1

This invention relates to new and useful improvements in gauges and the primary object of the present invention is to provide a device for indicating the angular relationship between the head and the shank of a golf club.

Another important object of the present invention is to provide a golf club indicator including a base member and a plurality of units that are quickly and readily applied to or removed from the base member so that the angular relationship between a golf club shank and head can be determined as well as the vertical and horizontal inclination of the striking face of a golf club head.

Yet another object of the present invention is to provide a golf club indicator including a base member, a footing carried by the base member and embodying novel and improved means for clamping the head of a golf club against the footing.

A further object of the present invention is to provide a golf club indicator including a footing upon which the head of a golf club is supported and a novel and improved gauge unit for urging the head of a golf club against the footing.

A still further aim of the present invention is to provide a golf club indicator that is simple and practical in construction, strong and reliable in use, small and compact in structure, neat and attractive in appearance, efficient and durable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present invention assembled for use in determining the angular relationship between the head and shank of a golf club (shown in dotted lines);

Figure 2 is a side elevational view of Figure 1;

Figure 3 is an end view of Figure 2;

Figure 4 is an enlarged fragmentary, horizontal, longitudinal sectional view taken substantially on the plane of section line 4—4 of Figure 2;

Figure 5 is an enlarged, fragmentary, vertical sectional view taken substantially on the plane of section line 5—5 of Figure 2;

Figure 6 is an enlarged sectional view taken substantially on the plane of section line 6—6 of Figure 2;

2

Figure 7 is a perspective view of the base member used in conjunction with the present invention;

Figure 8 is an enlarged fragmentary side elevational view showing the loft indicating unit in use;

Figure 9 is a sectional view taken substantially on the plane of section line 9—9 of Figure 8;

Figure 10 is a fragmentary top plan view of the present invention and showing the slice and hook indicator unit in use; and,

Figure 11 is a fragmentary side elevational view of Figure 10.

Referring now to the drawings in detail, wherein for the purpose of illustration, there is disclosed a preferred embodiment of the present invention, the numeral 10 represents an elongated base member having one end 12 fixed to the central portion of a cross channel 14. The remaining end 16, of the base member 10 is provided with an elongated recess or slot 18 in its upper surface for a purpose which will later become more fully apparent.

A substantially rectangular footing or bearing block 20 is mounted in the cross channel 14 and includes an upper flat surface 22.

Means is provided for clamping the head 24 of a golf club 26 against the upper flat surface 22 of the footing 20 and this means comprises a bracket or angulated strap 28 that is fixed to the cross channel 14. The bracket 28 includes a horizontally extending arm 30 that supports an internally threaded sleeve 32. The sleeve 32 is concentric with an opening in the arm 30 and receivably engages a screw or threaded rod 34 having a hand grip 36 at its upper end.

A pressure member 38 is swiveled, as at 40, to the lower reduced end of the rod 34 and the pressure member includes a resilient pad 42 having a lower concaved surface 44.

The numeral 46 represents a carriage or sliding member having its lower edge received in the slot 18. Pins 48 project laterally from the lower end of the carriage 46 and are slidably received in longitudinal slots or guide openings 50 provided in the side faces of the base member 10.

Means is provided for moving the carriage longitudinally of the base member 10 and toward or away from the cross channel 14. This latest means comprises a pair of spaced parallel rack bars 52 and 54 that are detachably secured to the upper face of the base member 10.

A bearing sleeve 56 is carried by the carriage 46 and receives a manually rotatable shaft 58 having end portions 60 and 62 on which there is

keyed a pair of toothed wheels or gears 64 and 66 that engage the rack bars 52 and 54. A finger grip 68 is secured to the shaft whereby the same may be conveniently rotated.

The central portion of an elongated support 70 is pivoted, as at 72, for vertical movement on the carriage 46. The support 70 is provided with rearwardly converging edges 74 and 76 and a pointer 78 projects outwardly from the point where the edges 74 and 76 meet. The pointer 78 is registerable with a graduated plate 80 secured to the carriage 46.

A pair of co-axial hooks 82 and 84 project outwardly from the forward concaved edge 86 of the support 70 and receive the handle portion 88 and shank portion 90 of the golf club 26. An elongated coil spring 92 is anchored at one end to a loop 94 on the central portion of the edge 86 and the other end of the spring 92 is provided with a hook that embraces the shank of the golf club to yielding retain the shank and handle portion of the golf club in the hooks or V-shaped seats 82 and 84.

In practical use of the present invention the head of the golf club is first clamped against the upper surface 22 of the footing 20 and then the shank 90 is placed in the seats 82 and 84 and held therein by the spring 92. Next it is merely necessary to read the indicia on plate 80 indicated by the pointer 78 to determine the angular relationship between the shank 90 and the flat lower face of the head 24.

Attention is now directed to Figures 8 and 9 wherein there is disclosed the unit for determining the angular relationship between the lower flat face 100 of the golf club head 24 and the striking face 102 of the head 24. This unit 104 replaces the carriage 46 and consists of another carriage 106 having a hand grip 108 applied thereto so that the carriage can be moved in the slot in the cross channel 14.

A swinging member 110 is pivoted, as at 112, to one side face of the carriage 106. One end of the member 110 supports a U-shaped pressure member or bearing member 114 and the other end of the member 110 supports a pointer 116 that registers with a graduated plate 118 secured to one side face of the carriage 106.

In practical use of the unit 104 the face 100 of the golf club head 24 is held against the upper flat surface 22 of the footing 20 and the carriage 106 is moved until the member 114 bears against the striking face 102 of the golf club head 24. Next the indicia or degree at which the pointer is placed on the plate 118 is determined.

Reference is next directed to Figures 10 and 11, wherein there is disclosed the unit for determining the angular relationship between the striking surface 102 and the lower face 100 and hence the hook or slice of the golf club. This latest unit 120 includes a carriage 122 having its lower portion slidably received in the cross channel 14.

The carriage 122 is provided with a hand grip 124 so that the same can be moved toward and away from the footing 20 on which the golf club head 24 is supported.

A swinging member or support 126 is pivoted, as at 128, to the upper flat face of the carriage 122. A bearing member or U-shaped element 130 is secured to one end of the member 126 and a pointer 132 at the other end of the member 126 registers with a graduate plate 134 mounted on the upper flat face of the carriage 122.

When the member 130 bears against the strik-

ing face 102, an angle can be read upon the plate 134.

It should be noted, that if the intended, and predetermined, angular relationship between the shank and head is not correct an additional coating of lacquer is applied to the lower flat face of the golf club head or the lower flat face is sanded, depending of course, whether the angle is too great or too small. This procedure is also followed with the use of the units 104 or 120 for obtaining the proper hook, slice and loft of the golf club.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A golf club indicator comprising a base member, a footing mounted on said base member, means carried by said base member for clamping the head of a golf club against the footing and including a vertically adjustable member overlying the footing, a carriage movable on said base member, gripping means carried by said carriage for engaging and holding the shank and handle of a golf club and indicating means mounted on the carriage for determining the angle between the head and the shank of a golf club.

2. The combination of claim 1 and means for moving the carriage in a step by step adjustment on the base member.

3. The combination of claim 2 wherein said means for moving the carriage in a step by step adjustment on the base member includes a rack bar mounted on said base member, a manually rotated shaft journaled on said carriage, and a gear keyed on said shaft and engaging said rack bar.

4. A golf club indicator comprising a base member, a footing mounted on said base member, means carried by said base member for clamping the head of a golf club against the footing, a carriage movable on said base member, a swingable support pivoted to said carriage, means carried by said support for engaging the shank and handle portion of a golf club, means carried by said support holding the shank and handle portion of a golf club against said engaging means and indicating means mounted on the carriage for determining the pivotal movement of the support relative to the carriage for indicating the angle between the head and shank of a golf club.

5. A golf club indicator comprising a base member, a footing mounted on said base member, a vertically adjustable head carried by said base member and overlying said footing for clamping the head of a golf club against the footing, a carriage movable on said base member, a vertically swingable support pivoted to said carriage, means carried by said support for engaging and holding the shank and handle portion of a golf club on said support, a pointer fixed to said support, and a graduated plate mounted on said carriage and registerable with said pointer to indicate the angle between the head and shank of a golf club.

6. The combination of claim 5 and means for adjusting the carriage longitudinally upon the base member and relative to the footing, said adjusting means including a pair of spaced parallel rack bars mounted on said base member, a manually rotatable shaft journaled on said carriage, and a pair of toothed wheels carried by said shaft and engaging the rack bars.

7. The combination of claim 5 wherein said support includes a pair of co-axial hook members for embracing the shank and handle portion of a golf club.

8. The combination of claim 5 wherein said means carried by said support for engaging and holding the shank and handle portion of a golf club relative to said support includes an elongated spring member mounted on said support and having a terminal hook for embracing the shank of a golf club.

9. A golf club indicator comprising an elongated base member, a footing mounted at one end of said base member, means carried by said base member at the same end of the base member as said footing for clamping the head of a golf club against the footing, a carriage movable on said

base member, means carried by said carriage for engaging the shank and handle of a golf club, and indicating means mounted on the carriage for determining the angle between the head and the shank of a golf club, said means carried by said base member for clamping the head of a golf club against the footing including a holding arm, an internally threaded sleeve carried by said holding arm, a screw threaded in said sleeve, and a pressure member swiveled to said screw.

10. The combination of claim 9 wherein said pressure member includes a resilient block having a concaved lower face.

ALBERT H. BRYANT.
